LOCKING CONSTRUCTION FOR PAPERBOARD CARTONS

Orison W. Stone, Valley Cottage, N.Y., assignor to Continental Can Company, Inc., New York, N.Y., a corporation of New York

Filed June 24, 1957, Ser. No. 667,494

1 Claim. (Cl. 206—65)

The invention relates to a locking tongue and slot construction for the overlapping flaps of a wrap-around paperboard carton for packaging canned goods.

Ordinary tongue and slot locking devices sometimes slip and allow a wrap-around carton band to become loosened. This can be particularly troublesome in using this type of carton for the packaging of products contained in tin cans, because loosening of the package may allow the cans to become disengaged and fall out of the open ends of the carton. I have discovered how to prevent, or minimize the extent of, slippage between the tongue and slot as employed for locking the overlapping ends, or end flaps, of a wrap-around carton band for packaging goods contained in cans arranged in parallel rows. According to my invention, the locking tongue of one flap is foldable about a line at the base of the tongue aligned with an edge of the slot in the other flap when the flaps are in closed position, in which position the tongue and slot are adjacent the space between four of the cans. The tongue has locking ears which extend beyond the ends of the slot and which, after the tongue has been pushed inwardly through the slot, extend into engagement with adjacent sides of the cans. This engagement of the locking tongue with the sides of the cans holds the tongue in a position projecting downwardly between the containers and thereby assists in preventing slippage between the tongue and slot and consequent loosening of the package. Also, the locking ears of the tongue form shoulders for engagement with the chines of the cans to assist further in preventing slippage between the tongue and slot.

With reference to the accompanying drawings, I shall now describe the best mode contemplated by me for carrying out my invention.

Fig. 1 is a face view of the inside of a carton blank embodying my improved locking arrangement.

Fig. 2 is a side elevational view showing the carton being wrapped around the cans.

Fig. 3 is a top plan view of the package. One of the two locking tongues has been pushed through its slot, the other not.

Fig. 4 is an enlarged detail view, in vertical cross section on the line 4—4 of Fig. 3, showing how the shoulders of the locking ears of the tongue engage the chines of the cans.

Fig. 5 is a diagrammatic view, which may be considered as an enlarged vertical cross section on the line 5—5 of Fig. 4, illustrating how my construction assists in preventing slippage between the tongue and slot.

Fig. 6 is a similar diagrammatic view, illustrating the possible effects of omitting the special structural features of my locking device.

Fig. 1 shows the blank for a wrap-around paperboard carton for packaging six cans C arranged in two parallel rows of three cans each. In this general type of carton suitable means are provided for holding the cans in place once the carton has been wrapped tightly around them, but, as such can-holding means are well known in the

2

art, it will be unnecessary to describe them here. The ends of the carton band terminate in overlapping flaps 7 and 8. A slot, or slots 9 in one of the flaps cooperates with a complementary tongue, or tongues 10, in the other. 5 Once the carton band has been wrapped around the cans in the manner indicated in Figs. 2 and 3, the tongues, which are wider than the slots, are pushed through the slots. The tongue 10 at the top of Fig. 3 is ready to be pushed through the slot; that at the bottom of the 10 same figure has been pushed through.

Each of the locking tongues 10 is foldable about a score line 11 at the base of the tongue aligned with edge portion 12 of slot 9 when the flaps are in closed position with the tongue flap 8 above the slot flap 7. 15 In this position (Fig. 3) the tongue and slot are adjacent the space between four of the cans. The tongue has locking ears 13 (Fig. 4) which extend beyond the ends 14 of the slot and which, after the tongue has been pushed inwardly through the slot, extend into engagement with the sides of the cans so as to hold the tongue in a position projecting downwardly between the containers (Figs. 3 and 4) and thereby assist in preventing slippage between the tongue and slot and consequent loosening of the package. The locking ears are formed 20 with shoulders 15 for engagement with the chines 16 of the cans to assist further in preventing slippage between the tongue and slot. How this is accomplished will now be explained with reference to Fig. 5.

In Fig. 5, we see the tongue 10 with its locking ears 30 in engagement with the left-hand container C. This holds the tongue against springing back toward the plane of the flaps 7 and 8, and helps keep the tongue from being pulled out of its alignment with the edge 12 of the slot. The forces tending to pull the flaps 7 and 8 apart 35 in the directions of the arrows F₁ and F₂ thus are resisted by a bearing of the surface of the tongue against the whole side 12 of the slot instead of just by the engagement between the edges of ears 13 and the ends 14 of the slot. With this arrangement, which takes the tearing 40 load off the locking ears and slot ends, there is much less tendency to tearing and distortion such as otherwise would permit the package to become loosened. As seen in Fig. 5, forces F₁ and F₂ may be considered to be resisted at R₁ by the force of reaction at edge 12 of the slot, acting in conjunction with the force of reaction 45 at R₂ where the tongue bears against the sides of the cans. R₁ and R₂ produce a couple resisting the torque tending to rotate tongue 10 in a clockwise direction. If permitted to rotate into a position such as shown at 10' in Fig. 6, the tongue would lose much of its locking 50 effectiveness. Its movement into position 10' is resisted further by engagement between shoulders 15 of the tongue and chines 16 of the cans. The result is to maintain the full overlap between flaps 7 and 8 of the 55 carton, as diagrammatically suggested by vertical alignment of given points a and b of the flaps. Fig. 6 illustrates the possible effects of omitting the special structural features I have described. Notice that here the flaps 7 and 8 have pulled apart to the extent suggested 60 by vertical mis-alignment between the given points a and b of the flaps. Resistance to pulling the flaps apart is no longer furnished by a bearing of the surface of the tongue against the side 12 of the slot because the 65 unforesighted upward movement of the tongue has allowed the base of the tongue to pull up over the side of the slot, throwing the locking burden entirely upon the edges of locking ears or upon whatever other secondary attachment may have been provided.

The terms and expressions which I have employed are used in a descriptive and not a limiting sense, and I have no intention of excluding such equivalents of the

invention described, or of portions thereof, as fall within the scope of the claim.

I claim:

A carton package comprising a paperboard carton wrapped around goods contained in cylindrical containers such as metal cans having chines, said containers arranged in parallel rows within the carton, said carton having overlapping flaps, a slot in one of the flaps and a complementary locking tongue in the other flap, the locking tongue and slot positioned adjacent the space 10 between four of the cylindrical containers and the locking construction being characterized as follows: the locking

tongue extending inwardly of the package at nearly a right angle to the flaps and having positioning ears extending laterally from each side thereof between adjacent pairs of said four containers, said positioning ears engaging the chines of at least two adjacent containers.
